UNITED STATES PATENT OFFICE.

MAX SIELAFF, OF BERLIN, GERMANY.

POST-STAMP-VENDING APPARATUS.

No. 831,113.

Specification of Letters Patent.

Patented Sept. 18, 1906.

Application filed August 22, 1904. Serial No. 221,763.

To all whom it may concern:

Be it known that I, MAX SIELAFF, manufacturer, a subject of the King of Prussia, German Emperor, and a resident of 23 Spenderstrasse, Berlin, Kingdom of Prussia, German Empire, have invented a new and useful Post-Stamp-Vending Apparatus, of which the following is an exact specification.

My invention relates to coin-controlled vending devices, especially those used for selling post-stamps, tickets, and other articles which are taken off from a strip; and its object is to avoid the incorrect action of the apparatus hitherto used. The parts of such strips of post-stamps or tickets are not exactly of the same length, and therefore it is difficult to move the strips automatically as precisely as is necessary for a good working of the apparatus.

Several constructional forms of the invention are illustrated.

Figures 1 to 6 show in side views the principal arrangement of the device in different positions of working. Fig. 1 shows the paper strip, being in the original position; and Figs. 2, 3, 4, 5, 6 show several other positions of the paper strip, showing the working of the apparatus. In Figs. 7 to 10 a side view of a constructional form of the device is illustrated, showing the members in different positions in the same manner as before.

My invention consists, principally, in moving the paper strip more than to the length of the ticket or stamp which is to be delivered and then after having separated the ticket from the strip to control and to regulate the position of the paper strip so that it returns to its normal position.

The chief arrangement of the device illustrated in Figs. 1 to 6 is the following: The ticket or stamp strip $s^1 s^2 s^3$ is perforated at $s^4 s^5$ in the well-known manner. Each part between two perforations or several parts is to be correctly delivered by the apparatus to the customer. $a a'$ are two rollers, a' having two recesses $c c$. $b b'$ are two rollers arranged beneath the rollers $a a'$. d is an arm attached to the lever e at the point d , the lever e being allowed to swing round the axle e' . e^2 is a spring pressing the lever e to the right side toward the cam g , whereby the pin e^2 on the lever e is forced toward the cam g .

The working of the device as illustrated in Figs. 1 to 6 is as follows: The stamp-strip being in the position of Fig. 1 rests on the

arm d , and thereby a distinct position of the strip is secured, the strip being and lying loose in the recess c of the rollers $a a'$. When the rollers $a a' b b'$ are moved in the direction of the arrows $r r'$, they come in the position 60 illustrated in Fig. 2, and the paper strip begins to be fed by $a a'$. At this moment, when the feeding operation begins the arm d is withdrawn by the rotating cam g by means of the pin e^2 on the lever e , and the paper 65 strip takes the positions in Fig. 3 and then in Fig. 4. In the position of Fig. 4 the paper strip is grasped by the rotating rollers $b b'$ and drawn downward. The rollers $b b'$ revolve more quickly than the rollers $a a'$, and 70 it is clear that as soon as the rollers $b b'$ have firmly grasped the strip part s' and the perforated part s^4 being free from the rollers $a a'$, Fig. 4, the strip must be divided and a separated part s' is formed. To assist the dividing 75 action, the arm d may be pushed forward by the spring e^3 toward the strip $s' s^2$, as shown in Fig. 5, the cam g having released the pin e^2 . It is obvious that the dividing operation 80 can be brought into effect by one of these devices or by both. The separated part s' of the strip is further fed by the rollers $b b'$, thrown out, and delivered to the customer. The part s^2 of the strip is held between and by the rollers $a a'$, and it is of importance to secure now the exact normal position of the strip, so that its end gains the position shown 85 in Fig. 1, and that is accomplished by the arm d , which is already in the position shown in Fig. 5. The recess c has released the strip 90 from the influence of the rollers $a a'$. As seen in Fig. 6, the rollers $a a'$ have left free the remaining paper strip $s^2 s^3$, and the end of the paper strip touches the arm d and rests on it in the same manner as seen in Fig. 1. In 95 this way always the correct normal position of the end of the ticket-strip or stamp-strip is insured, and the differences and the surplus in the movement of the strip by the rollers $a a'$ are eliminated, according to the effect of the 100 supporting-arm d and of the recesses c . The chief point is that the end of the strip or distinct point of the strip is always in a distinct position secured by the arm d .

It is obvious that it is possible to transport 105 and deliver two or three parts of the strip in the same manner as described. Furthermore, it is obvious that instead of the rollers $a a'$ a pair of tongs may be employed, which move the strip and are opened when the end of the 110

strip rests on the arm *d*. Instead of the recesses *c* on the roller *a'* a pair of rollers may be employed, which are not firmly arranged onto another, but may be removed one from another a short time, so that the end of the strip may gain its original position supported by the arm *d*. Naturally the arm *d* can hold the paper strip at any point desired, and it is not necessary that the paper strip be held at its end.

It has been supposed that the paper strip has always fed forward farther than necessary, and the arrangement of the described device, Figs. 1 to 6, is such that the faults arising from this overfeeding are eliminated; but it is possible that the paper strip is not fed forward or as far as is necessary, and to compensate this the following device is provided, which is now to be described, and which is illustrated in Figs. 7 to 10. The arrangement of the rollers is the same as in Figs. 1 to 6, and the same letters are employed for the same mechanisms. The arm *d*, which supports the end of the paper strip, is provided with a projection *d*², and above the arm *d* is arranged a second arm *e*⁴ with a projection *e*⁵. The arm *e*⁴ is bent near its end at a right angle and forms a projection *e*⁶. The projection *e*⁶ and the projection *d*² of the arm *d* form tongs, and the arm *e*⁴ rests by means of the projection *d*² on the arm *d*. The lever *e*, which is moved in the manner already described by the two cams *g* and *f*, is illustrated in its original position in Fig. 7. In this position the tongs *d*² *e*⁶ have grasped the end of the paper strip and hold it fast in its correct position. If the rollers *a* *a'* *b* *b'* are moved in the direction of the arrows *r* *r'*, the paper strip *s'* is moved downward by the rollers *a* *a'* and in the same moment the arm *d* is moved back by the cam *f*. The end of the paper strip is free and is brought between the rollers *b* *b'* in the manner as is shown by Figs. 3, 4, and 5, and the last part of the strip *s'* *s*² *s*³ is separated in the manner as illustrated in Fig. 5. The arm *d* is now released from the cam *f* and takes the position, Fig. 9—that is to say, the most exterior part of the arm stands beneath the end of the paper strip *s*². It is clear that when the paper strip has not been transported enough there will be a free space between the most exterior part of the arm *d* and between the end of the strip *s*². It is clear that this is not a correct position of the end of the strip, and to bring this end of the paper strip into the position as shown in Fig. 7 it is necessary to grasp the end of the strip and to move it downward, and this is effected by the nose or projection *d*² of the arm *d* and by the projection *e*⁶ of the arm *e*⁴ in the following manner: The arm *d* has been raised by the action of the cam *f* and brought into the position shown in Fig. 10, and the arm *e*⁴ being supported by the arm *d* by means of the projection *e*⁶ is raised in the

same manner, so that the two projections *d*² and *e*⁶ stand in the position, Fig. 10. They form an open tongs, and these tongs are closed by means of the cam *g*, as clearly shown in Fig. 7, so that the ends of the paper strip is grasped, and then the arm *d* has become free from the action of the cam *f*, both arms *d* and *e*⁴ sink down by their own weight and move the paper strip in the correct position, Fig. 7. It is obvious that the raising and the lowering of the arms *d* and *e*⁴ with the tongs *d*² and *e*⁶ must be chosen, so that the greatest differences which may occur in the feeding of the paper strip are eliminated and regulated by these elements and movements.

Having thus fully described the nature of my invention, what I desire to secure by Letters Patent of the United States is—

1. Vending apparatus for stamps, tickets and other paper strips, which are to be separated, consisting of means for feeding the paper strip to a second feeding device, means for separating a part of the paper strip, and means for adjusting that part of the paper strip which remains when the separation has taken place in a correct end position, substantially as described.

2. Vending apparatus for stamps, tickets and other paper strips, which are to be separated, consisting of two rollers *a* *a'* for feeding the paper strip to a second feeding device, consisting of two rollers *b* *b'* rotating in the same direction as the rollers *a* *a'*, means for separating a part of the paper strips and means for adjusting that part of the paper strip which remains when the separation has taken place in a correct end position, substantially as described.

3. Vending apparatus for stamps, tickets and other paper strips, which are to be separated, consisting of two rollers *a* *a'* for feeding the paper strip to a second feeding device, consisting of two rollers *b* *b'* rotating in the same direction as the rollers *a* *a'* and somewhat more quickly, thus separating a part of the paper strip, and means for adjusting the remaining paper strip in a correct end position, substantially as described.

4. Vending apparatus for stamps, tickets and other paper strips, which are to be separated, consisting of two rollers *a* *a'* for feeding the paper strip to a second feeding device, consisting of two rollers *b* *b'* rotating in the same direction and somewhat more quickly than the rollers *a* *a'*, thus separating a part of the paper strip, in combination with two levers *d* *e* having alternating motion and operated by the cam *g* *f* to assist the dividing of the paper strip, and means for adjusting the remaining paper strips in a correct end position, substantially as described.

5. Vending apparatus for stamps, tickets and other paper strips, which are to be separated, consisting of two rollers *a* *a'* having

recesses *c* and of two rollers *b b'*, in combination with two levers *d e* having alternating motion, and operated by two cams *g f* and with a third lever *e'* operated by the lever *d* which lever *e'* together with the recesses *c* serves for attaching the remaining paper strip in a correct end position, substantially as described.

In testimony whereof I have signed my name to this specification in the presence of ~~1c~~ two subscribing witnesses.

MAX SIELAFF.
